STUFFING BOX

James S. Abercrombie, Houston, Tex.

Application December 27, 1937, Serial No. 181,834

6 Claims. (Cl. 286—38)

The invention relates to a balanced pressure stuffing box wherein the pressure which is being packed against serves the purpose of maintaining a pressure to resist leakage.

Particularly in oil field equipment, abrasive liquids such as drilling muds must be pumped under enormous pressures. It is needless to say that a drilling mud is very abrasive and results in excessive wear upon rods, shafts and packings and it is with a view of providing a construction wherein a reserve of lubricant or non-abrasive liquid can be stored at a location adjacent the packing in such a manner that the pressure which is being packed against will be available against this reserve of lubricant to balance the pressure of the abrasive liquid on the stuffing box or packing.

It is another object of the invention to provide a reserve of lubricant for stuffing boxes which is stored in a resilient container subjected to the pressure which is being packed against.

Another object of the invention is to prevent wear on rods, shafts and packings by utilizing the pressure which is confined to inject the lubricant into the packing and about the rod or shaft.

It is one of the objects of the invention to provide a resilient sleeve container for lubricant for stuffing boxes.

Other and further objects of the invention will be readily apparent when the following description is considered in connection with the accompanying drawing, wherein the figure in the drawing illustrates a vertical sectional view of the structure for practicing the invention.

Pressures approximating 1500 and 2000 pounds per square inch are constantly maintained in the pumps for circulating this drilling mud as well as the swivels which support the drill pipe and conduct the mud into the well. There is considerable leakage, due to the fact that the abrasive liquid will coat the rods and tubes or shafts of the parts so that when there is either reciprocation or rotation thereof, the abrasive will be carried with the rod into the packing. This abrasive liquid is of course under pressure, which tends to force it into the packing so that in many instances the rods and shafts or tubes will be quickly cut away as the packing becomes saturated with abrasive.

In order to protect the packing and to introduce the lubricant therein, an attachment has been devised and, as seen in the drawing, the packing box is indicated generally at 2 and has been illustrated as either a portion of a slush pump, a drilling swivel or other pieces of equipment.

ment wherein the rod, shaft or tube 3 is to be rotated or reciprocated relative to the stuffing box 2. It will be understood that liquid or fluid under pressure is within the chamber 5 and it is intended that this abrasive liquid in the chamber 5 will be excluded from the stuffing box 2. It is to be understood that the member 3 may be hollow or solid.

A support or body 10 has an upstanding collar 11 thereon which provides a recess 12 to receive the packing member 13. This packing is held in position by a gland 14 which is adjustably received in the upper end of the collar 11. The rod, shaft, or tubing 3 passes through the gland and the packing.

The support or body 10 may be fixed to a suitable structure 15 such as the housing of a swivel or a pump. It is to be understood, however, that the present invention may be applied at any desirable location where an abrasive is to be excluded from a packing assembly.

In the drawing the body 10 is shown as having been provided with a depending skirt or frame 17 which may be made integrally of the body or may be connected thereto. This skirt has a plurality of spaced leg portions 18 extending therefrom which carry a collar 19. The legs 18 may be of any desired length, depending upon the volume of lubricant or non-abrasive substance which is to be deposited into chamber 21. The skirt 17 and the head 19 are each provided with an outstanding rib 22 which is so spaced as to provide an undercut groove 23. A resilient sleeve 25 of rubber or other suitable material is adjusted about the skirt and head as well as the legs 18 and is provided with an enlarged end 26 to fit into grooves 23. While this supporting frame 24 has been shown in the drawing as integral, it is obvious that it may be made in parts for purpose of suitable assembly unless it is desired to expand the sleeve 25 and pass it over the head.

In order to close the lower end of the chamber 21 a porous packing 30 is disposed in the recess 31 and held in position by a gland 32.

In order that lubricant or other suitable non-abrasive liquid or fluid may be injected into the chamber 21 a passage 35 has been shown in the support 10. This passage leads into the opening 36 in the body 10 through which the rod or shaft 3 passes and may be controlled by a suitable closure member 37 of any desired type.

In operation the parts will be assembled as shown in the drawing and a suitable volume of non-abrasive substance will be injected into the chamber 21 to fill the chamber and possibly to 55

distend the sleeve 25 somewhat. The pressure at which this lubricant is injected will vary of course in accordance with the pressure which it is contemplated will be present in the chamber 5 and probably the pressure inside the chamber 21 will be at least equal to and possibly greater than the pressure in the chamber 5.

With the parts in this condition operation will begin and it seems obvious that the pressure in the chamber 5 will be exerted on the resilient sleeve 25 so as to force lubricant along the shaft 3 into the area of the packing 13. If there is any wear or vibration of the rod or shaft which would permit leakage through the stuffing box 2 then of course it will be the lubricant or non-abrasive liquid which will feed through the opening 36 and into the packing and it will be impossible for the abrasive material in the chamber 5 to reach the packing 13. This non-abrasive material will be constantly forced into the packing due to the resiliency of the sleeve 25 which is subjected to the pressure of the chamber 5. As leakage occurs the sleeve will gradually be forced to contract. Additional lubricant may be injected into the chamber 21 at desired intervals to replace the leakage.

There can be no leakage of abrasive fluid inwardly around the shaft through the base 19 because the packing 30 is of a porous nature and the pressure thereon will be balanced inside and outside along the shaft 3 because of the resilient nature of the sleeve 25. The lubricant will pass along the shaft 3 and saturate the porous packing 30 and of course there will be no differential pressure along the shaft at this packing 30 because of the resilient nature of the sleeve 25.

From the foregoing it seems obvious that the pressure which is being packed against is utilized to maintain a seal of lubricant to prevent abrasion.

The large capacity of the chamber 21 will obviate frequent attention and when the device is once assembled and filled with lubricant it will operate for long periods of time because the lubricant will gradually be fed into the packing by the pressure being packed against.

What is claimed is:

1. A packing assembly including a support, a packing on one side thereof, a lubricant container on the other side thereof, means to introduce lubricant into said container, said container having a rigid frame and a resilient portion subjected to the pressure being packed against so that the lubricant is fed to said packing by such pressure, and a second packing on said container

which is also subjected to the pressure of the lubricant.

2. A packing assembly including a pair of spaced packings, and a reservoir for lubricant, said reservoir being disposed between said packings and having a rigid frame and a resilient portion so that the packed pressure will feed lubricant into said packings. 5

3. A packing assembly including a packing having a porous packing member, and a reservoir for lubricant, said reservoir including a rigid frame being disposed outside of said packing, a resilient portion on said reservoir subjected to the packed pressure so that the pressure on said packing will be balanced with the lubricant tendency to prevent entrance of the packed pressure. 10 15

4. An attachment for lubricating packings comprising a frame, a resilient sleeve thereon, means to affix said frame at the inner end of the packing, a stuffing box at the end of said frame, 20 and means to introduce lubricant inside of said sleeve so that such lubricant will be maintained at the pressure being packed against.

5. A housing containing fluid under pressure, an opening therein, a rod or tubular member 25 passing thru said opening and arranged for reciprocation or rotation, a stuffing box on the outside of said housing to form a seal about said member, a reservoir inside of said housing and about said member, said reservoir having a resilient portion yieldable against the pressure within said housing and a rigid portion to support said resilient portion, and means to introduce a non-abrasive substance into said reservoir to be maintained therein under the pressure in said housing and to be fed into said stuffing box by such pressure. 30 35

6. A housing containing fluid under pressure, an opening therein, a rod or tubular member 40 passing thru said opening and arranged for reciprocation or rotation, a stuffing box on the outside of said housing to form a seal about said member, a reservoir including a rigid frame inside of said housing and about said member, said reservoir having a resilient portion yieldable 45 against the pressure within said housing, and means to introduce a non-abrasive substance into said reservoir to be maintained therein under the pressure in said housing and to be fed into said stuffing box by such pressure, and a packing 50 about said member at the inside end of said reservoir to be subjected to the inside pressure of said reservoir.
